UNITED STATES PATENT OFFICE.

JOSEPH H. STALEY, OF KNIGHTSTOWN, INDIANA.

PRESS FOR REMOVING BUSHINGS AND THE LIKE.

1,352,098.

Specification of Letters Patent.

Patented Sept. 7, 1920.

Application filed August 11, 1919. Serial No. 316,634.

To all whom it may concern:

Be it known that I, JOSEPH H. STALEY, a citizen of the United States, residing at Knightstown, in the county of Henry and 5 State of Indiana, have invented a new and useful Press for Removing Bushings and the like, of which the following is a specification.

This invention relates to tools, and more 10 particularly to a tool used for removing or displacing bushings, from their supports.

The primary object of the invention is 15 to provide a device of this character in the form of a press, for gradually forcing the bushing from the seat, thereby eliminating the necessity of hammering the bushing, which hammering often results in breaking the support, or arm, in which the bearing 20 is mounted.

A still further object of the invention is 25 to provide a device of this character which will force the bushing from its support, and deposit the same on the ground, or floor directly under the tool, obviating the necessity of removing the bushing from the tool.

With the foregoing and other objects in 30 view which will appear as the description proceeds, the invention resides in the combination and arrangement of parts and in the details of construction hereinafter described and claimed, it being understood that changes in the precise embodiment of 35 the invention herein disclosed, may be made within the scope of what is claimed without departing from the spirit of the invention.

Referring to the drawings:—

40 Figure 1 illustrates a side elevational view of a bushing press, constructed in accordance with the present invention.

Fig. 2 illustrates a sectional view taken on line 2—2 of Fig. 1.

45 Having reference to the drawing in detail, the reference character 10 indicates the body of the press, which is formed of cast iron, or other suitable cast material, and includes the upper arm 11, extending at right 50 angles to the upper portion of the body 10, and provided with the threaded opening 12, intermediate its length, and extending throughout the width, or thickness of said arm 11.

5 Formed integral with the lower portion

of the body 10, of the tool, is the right angle arm 13, also provided with an opening 14 extending therethrough, said opening 14 having a recessed portion 15, forming the upper part of the opening, for purposes to 60 be hereinafter more fully described.

The power element, of the press includes the rod 16, threaded throughout a portion of its length, and having a reduced portion 17 formed at the lower end thereof, the reduced portion 17, being of a diameter equal to the interior diameter of the opening 14, to allow said reduced portion 17 to move throughout the length of said opening 14, thereby forcing an article, engaged by the 70 lower end of the reduced portion 17 through said opening 14, where the same is deposited or released from its connection with the power element.

As shown, the reduced portion 17, of the 75 power element, is provided with a reduced end section 18, which is of a diameter slightly less than the diameter of the interior of the bushing operated on, the reduced portion 18, forming with the lower 80 end of the reduced portion 17, the annular shoulder 19, which shoulder cooperates with the upper edge of the bushing, under operation, for holding the bushing and power element into engagement with each other, 85 and at the same time forms an abutment for forcing the bushing from its seat.

The upper end of the power element is provided with a head 20, which in turn is provided with a transverse opening 21, 90 through which extends the operating lever 22, the ends thereof being flattened to provide the shoulders 23, to prevent the operating lever 22 from being removed from the opening 21.

95 In operation, the power element is screwed to the limit of its upward movement, the right angle arms 11 and 13 substantially embracing the shaft or arm in which the bushing to be removed is supported, the lower end of the arm being positioned above recessed portion 15 of the opening 14, in order that the same will be held stationary. The operating lever 22 is then rotated to force the power element downwardly, until 105 the reduced section 18, positions itself within the opening of the bushing, so that further movement of the lever 22 will cause the bushing to be forced from the member supporting the same, the bushing contact- 110

ing with the recessed portion of the opening 14, to cause the bushing to be guided through said opening.

When the power element is in the position, as just described it will be seen that the annular shoulder engages the upper edge of the bushing, with the result that further rotation of the operating lever 22 and power element, causes the reduced portion 17 to move downwardly through the opening in which the bushing is supported, thereby forcing the bushing through the opening 14 formed in the right angle arm 13, of the tool.

15. The operating lever 22 is now rotated in the opposite direction, and the tool removed from the bushing.

It might be further stated that while the primary object of the invention is to provide a device for removing the bushing, 20 it might also be employed for inserting bushings in their seat.

Having thus described the invention, what is claimed is:—

25. 1. In a press, a body including arms extending at right angles thereto, one of said arms having a threaded opening, the oppo-

site arm having an opening extending therethrough, a power element including a threaded rod positioned in the threaded opening, 30 said threaded rod having a reduced portion and a relatively smaller reduced portion forming a part of the first mentioned reduced portion to provide an annular shoulder, the first mentioned reduced portion being equal 35 to the length of the thickness of the arms.

2. In a press, a body including arms extending at right angles thereto, one of said arms having a threaded opening, the opposite arm having an opening extending therethrough, the last mentioned opening having a recessed portion formed adjacent the upper end thereof, a threaded power element operating in the threaded opening, said power element having a reduced portion adapted 40 to move through the second mentioned opening.

In testimony that I claim the foregoing as my own, I have hereto affixed my signature in the presence of two witnesses.

JOSEPH H. STALEY.
